US00D930579S

(12) **United States Design Patent** (10) **Patent No.:** **US D930,579 S**
(45) **Date of Patent:** **** Sep. 14, 2021**

(54) **CHARGER**

(71) Applicant: **Guang Zhou Yun Zhong Cai Technology Co., Ltd.**, Guang Zhou (CN)

(72) Inventor: **Cai-Hong Zhong**, Guang Zhou (CN)

(73) Assignee: **GUANG ZHOU YUN ZHONG CAI TECHNOLOGY CO., LTD.**, Guang Zhou (CN)

(**) Term: **15 Years**

(21) Appl. No.: **29/658,933**

(22) Filed: **Aug. 3, 2018**

(51) LOC (13) Cl. **13-02**

(52) U.S. Cl.

USPC **D13/108**

(58) **Field of Classification Search**

USPC ..... D13/103, 110, 118-119, 184, 199, D13/107-108; D14/251, 253, 432, 434 CPC H02J 7/025; H02J 7/005; H02J 7/0026; H02J 7/0042; H02J 7/0044; H02J 7/0045; H02J 7/0013; H02J 7/0003; H02J 7/007; H02J 7/0027
